UNITED STATES PATENT OFFICE.

MERVIN F. WALT, OF HURON, SOUTH DAKOTA.

NECKTIE.

1,378,067.

Specification of Letters Patent. Patented May 17, 1921.

Application filed March 15, 1920. Serial No. 365,774.

To all whom it may concern:

Be it known that I, MERVIN F. WALT, a citizen of the United States, and a resident of Huron, in the county of Beadle and State 5 of South Dakota, have invented a new and useful Improvement in Neckties, of which the following is a full, clear, and exact description.

My invention relates to improvements in 10 neckties, and it consists in the combinations, constructions, and arrangements herein described and claimed.

An object of my invention is to provide a necktie which will not become wrinkled in 15 service.

A further object of my invention is to provide a device of the type described in which means is provided for holding a stick pin thrust therethrough to prevent the same 20 from being accidentally disengaged.

A further object of my invention is to provide a device of the type described that can be slidably moved between the wings of a collar easily, can be adjusted to a collar 25 readily, and which presents a neat and attractive appearance when folded and tied in an ordinary manner.

A further object of my invention is to provide a device of the type described which 30 is simple in construction and which is thoroughly practical commercially.

Other objects and advantages will appear in the following specification, and the novel features of the invention will be particularly 35 pointed out in the appended claims.

My invention is illustrated in the accompanying drawings, forming part of this application, in which—

Figure 1 is a plan view of the device, 40 partly cut away to show the inner lining;

Fig. 2 is a section along the line 2—2 of Fig. 1;

Fig. 3 is a front view of the device as it appears in service, a portion of the outer 45 cover being cut away.

It is a well known fact that a tie, such as is now in common usage, will become wrinkled after having been in service a short time. It is then difficult to adjust such a tie 50 to a collar and the tie, when adjusted, presents an unattractive appearance. Furthermore, it is difficult to press a wrinkled tie to restore the original appearance of the same. Such pressing injures the texture of 55 the outer cover and consequently ties of ordinary commercial type are discarded after

having been worn a comparatively short time.

A tie embodying my invention can be worn indefinitely and will retain its smooth 60 unwrinkled appearance.

In carrying out my invention, I provide an outer cover 1, which is of suitable fabric and is modeled in shape after an approved pattern. An inner lining of a conventional 65 pattern and shape is disposed within the outer cover 1. This inner lining consists of end strips of suitable fabric 2 and 3 and an intermediate strip 4 which is of elastic material, such as rubber. The intermediate 70 strip 4 is secured at its ends to the end strips 2 and 3 in any suitable manner, as by stitching 5. A relatively narrow strip of tape 6 is secured along each upper side edge of the intermediate strip 4 for a purpose 75 hereinafter set forth. Apertures 7 are provided in the intermediate strip 4 at a predetermined point intermediate its length. An auxiliary strip or patch 8 of elastic material is secured to the strip 4 by stitches 9, 80 as shown in Fig. 3 of the accompanying drawings, or may be secured thereto in any other suitable manner. The strip 8 covers the portion of the strip that would ordinarily be pierced by a tie pin 10. 85

From the foregoing description of the various parts of the device, the operation thereof may be readily understood. The tie is adjusted to a collar in the usual manner, a knot 11 being formed, as shown in Fig. 3. 90 When the tie is removed, the elastic strip 4, which was folded when the knot 11 was formed, will regain its original shape and will thereby prevent wrinkles from forming in the outer cover 1. 95

Furthermore, a tie pin inserted through the elastic strip 4 will remain in position, since a gripping pressure will be exerted against the shank of the tie pin by the elastic material. The auxiliary strip 8 of elastic 100 is provided to cover the portion of the strip 4 that would ordinarily be pierced by the tie pin and consequently the tie pin is inserted through both the strip 8 and the strip 4, and is more firmly maintained in position.

The apertures 7 permit the tie to be adjusted to a collar in an ordinary manner without the same assuming a bulky appearance at the knot 11. The knot is prevented from slipping by the portions of the elastic fabric about the apertures 7 in the strip 4 being pressed toward each other. 110

The strips 6 of tape along the side edges of the elastic strip 4 serve to prevent the elastic material in the strip 4 from being distorted laterally and also take up 5 the strain which would otherwise be placed on the cover of the tie when the same is being adjusted to a collar.

It will be obvious that a tie embodying 10 my invention can be worn until the outer cover is threadbare without pressing and will during the entire term of service present a smooth and unwrinkled appearance.

It is also obvious that forms of apparel 15 other than that illustrated in the accompanying drawings may embody my invention without departing from the spirit and scope thereof, as disclosed in the foregoing specification and set forth more particularly in the appended claims.

20 I claim:

1. A necktie comprising an outer cover of 25 fabric and an inner lining disposed within said outer cover substantially the entire length thereof, said inner lining consisting of end strips of fabric, an intermediate strip of elastic material secured at its ends to said end strips, said intermediate strip having openings formed therethrough intermediate its length, a strip of tape disposed 30 along each side edge of said intermediate elastic strip, and an auxiliary strip of elastic secured to said intermediate strip intermediate its length.

2. A necktie comprising an outer cover 35 of fabric and an inner lining disposed within said outer cover substantially the entire

length thereof, said inner lining including a strip of elastic material having an auxiliary strip of elastic superposed thereon, whereby pressure is exerted against a pin 40 inserted through said auxiliary strip of elastic and said first named strip of elastic, thereby tending to maintain said pin in position.

3. A neck tie comprising an outer cover 45 of fabric, and an inner lining disposed within said outer cover, said inner lining consisting of end strips of fabric, and an intermediate strip of elastic material secured at its ends to said end strips, said intermediate strip having an elongated opening formed therethrough intermediate its length and intermediate the side edges thereof. 50

4. A necktie comprising an outer cover 55 of fabric and an inner lining disposed within said outer cover, said inner lining consisting of end strips of fabric and an intermediate strip of elastic material secured at its ends to said end strips, and a strip 60 of tape disposed along each side edge of said intermediate elastic strip.

5. A necktie comprising an outer cover 65 of fabric and an inner lining disposed within said outer cover, said inner lining consisting of end strips of fabric and an intermediate strip of elastic material secured at its ends to said end strips, said intermediate strip having a plurality of spaced apart elongated openings formed therethrough intermediate its length and spaced 70 from the side edges thereof.

MERVIN F. WALT.
